UNITED STATES PATENT OFFICE

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY

THREAD-TENSIONING DEVICE

Original application filed February 18, 1927, Serial No. 169,203. Divided and this application filed March 29, 1928. Serial No. 265,542.

The present invention relates to thread tensioning devices and more particularly, to a tensioning device for the locking or shuttle thread of a lockstitch sewing machine.

5 The object of the invention is to provide a simple and efficient tensioning device for the locking or shuttle thread which acts automatically to maintain an even and constant tension regardless of changes in the resistance offered by the thread leading from the 10 bobbin to said device.

With this object in view, the several features of the invention consist in the devices, 15 combinations, and arrangement of parts hereinafter described and claimed, and together with the advantages to be obtained thereby, should be readily understood by one skilled in the art from the following description taken in connection with the accompanying drawings, in which Fig. 1 is a view in front elevation of the shuttle mechanism in connection with the needle and a portion of the work with the machine parts and the 20 needle and shuttle threads in the positions they assume when the needle is at the limit of its loop drawing stroke; Fig. 2 is a view in side elevation of the mechanism illustrated in Fig. 1; Fig. 3 is a central sectional view of the shuttle and bobbin case; and Fig. 4 25 is a view similar to Fig. 3 with the bobbin case broken away to show the thread tension plate on the inside wall of the shuttle.

The drawings illustrate one embodiment of the invention in the lockstitch horn shoe 30 sewing machine more fully described and illustrated in the inventor's pending application Serial No. 169,203, of which the present application is a division.

The work engaging devices of the machine 35 comprise a work supporting horn which is adapted to extend within the shoe, a presser foot cooperating therewith, work feeding devices, a straight hook needle, and an oscillating shuttle.

40 The tensioning device for the shuttle thread which forms more specifically the subject-matter of the present invention comprises a spring plate which bears yieldingly against the inner wall of the shuttle case.

45 The thread passes from the bobbin case

around the spring plate where it is held in frictional contact between the plate and the surface of the shuttle wall, and then back again to a point nearly in line with the axis of the bobbin, from where it passes directly 55 down to the work. With this construction, it is evident that any obstruction or tightening of the feeding thread will tend to pull the spring plate away from the surface of the shuttle wall and thus cause a correspond- 60 ing decrease in the shuttle tension.

Referring more specifically to the drawings, the straight hook needle is indicated at 6 and the shuttle cooperating therewith at 8. The shuttle is discoidal in shape and is 65 mounted to reciprocate in a raceway formed in a segmental holding ring 10 removably secured by screws 12 to a correspondingly shaped extension on a bracket 14 forming a 70 portion of the machine frame.

The tension device for the locking thread comprises a yielding spring plate 16 arranged to press the thread against a cooperating thread support formed by the inner surface of the cylindrical wall of the shuttle. This 75 thread supporting surface is concentric with and, therefore, parallel to the axis of the shuttle. The plate 16 is held in the shuttle by means of holding screws 18 and by an adjusting screw 20 by means of which the 80 tension exerted on the thread may be initially adjusted. The bobbin is supported on a stud 22 projecting from the rear wall of the shuttle and bobbin case centrally of the bobbin case and the bobbin thread leads from the bobbin through an opening 24 in the bobbin case 85 to a guiding notch in the free end of the tension plate 16. The bobbin thread then passes between the tension plate and the thread supporting wall of the shuttle to a second guiding notch 26 formed in the forward edge of the tension spring. The thread then passes inwardly towards the center of the shuttle and emerges through an opening 28 formed 90 in the bobbin retaining arm 30. From the opening 28 the bobbin thread leads to the work. With this arrangement of the tension plate, cooperating thread support and thread guides, it will be seen that a pull exerted on the thread leading from the tension plate to 95

100

the opening 28 and to the work will tend to swing the tension plate 16 inwardly away from the thread supporting surface and thereby decrease the frictional resistance offered by the tension plate to the passage of the thread. The result of this arrangement is that the tension on the thread leading from the tension plate to the work is maintained constant regardless of any variations in the resistance offered by the thread leading from the bobbin to the tension plate.

The invention having been described, what is claimed is:

1. A lockstitch sewing machine having, in combination, a discoidal thread case for the locking thread having provision for supporting a bobbin with its axis parallel to the axis of the thread case, and having a thread supporting surface on its inner wall substantially parallel to the axis of the bobbin, and a thread tension device arranged to press the thread outwardly against said surface in its passage from the bobbin to the work and to yield inwardly upon an increase in the resistance offered by the thread leading from the bobbin to said device.
2. A lockstitch sewing machine having, in combination, a discoidal thread case for the locking thread having provision for supporting a bobbin with its axis parallel to the axis of the thread case and having a thread supporting surface substantially parallel to the axis of the bobbin over which the thread passes in its passage from the bobbin to the work, a tension plate arranged to press the thread against said surface, and means for guiding the thread from the tension plate in a direction substantially radial of the thread case to cause the thread to draw the plate away from said surface and equalize the tension upon an increase in the resistance offered by the thread leading from the bobbin to the plate.
3. A lockstitch sewing machine having, in combination, a discoidal thread case for the locking thread having provision for supporting a bobbin with its axis parallel to the axis of the thread case and having a thread supporting surface over which the thread passes in its passage from the bobbin to the work substantially parallel to the axis of the bobbin and being provided with a thread delivery opening substantially in line with the axis of the bobbin, and a thread tension device arranged to press the thread yieldingly outward against said surface and to yield inwardly upon an increase in the resistance offered by the thread leading from the bobbin to said device.
60. In testimony whereof I have signed my name to this specification.

BERNARD T. LEVEQUE.
